(57) **CLAIM**

The ornamental design for a Fuselage for a quad-rotor convertible aircraft, as shown and described.

DESCRIPTION

FIG. 1 is a perspective view of a fuselage for a quad-rotor convertible aircraft showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The structural features depicted by broken lines in the drawings have been shown for the purpose of illustrating portions of the fuselage for a quad-rotor convertible aircraft that form no part of the claimed design.
